Filed Apr. 11, 1967, Ser. No. 6,626

Term of patent 14 years

(Cl. D61—1)

Fig. 4.

Fig. 5.

Fig. 6.

FIG. 1 is a side elevational view of a photographic enlarger, showing my new design;

FIG. 2 is a front elevational view;

FIG. 3 is an opposite side elevational view;

FIG. 4 is a fragmentary perspective view, to an enlarged scale;

FIG. 5 is a fragmentary side elevational view to the same scale as FIG. 4;

FIG. 6 is a fragmentary front elevational view, to the same scale as FIG. 4;

FIG. 7 is a fragmentary opposite side elevational view, to the same scale as FIG. 4;

FIG. 8 is a fragmentary top plan view, to the same scale as FIG. 4;

FIG. 9 is a fragmentary bottom plan view, to the same scale as FIG. 4; and

FIG. 10 is a fragmentary rear elevational view thereof, to the same scale as FIG. 4.

The drawing figures are shaded to indicate contrast in

appearance, and a portion of FIG. 9 is diagonally lined to indicate transparency. The fragmentary broken line electric connector is for illustrative purposes only, the dominant features of my new design being shown in solid lines in the drawing.

I claim:

The ornamental design for a photographic enlarger, as shown and described.
